FILING MACHINE

Leopold F. Glaude, Chicago, Ill.

Application September 16, 1942, Serial No. 458,497

8 Claims. (Cl. 76—4)

This invention relates generally to filing machines. The invention is particularly applicable to machines of this class designed for filing and otherwise finishing punch dies, especially such as have been previously roughed out to approximate size and that require filing, grinding and honing of surfaces that run to a shoulder.

The main objects of this invention are to provide an improved filing machine in which the file or other abrading implement is mounted above the work and reciprocated vertically with proper provision for adjusting the stroke to work on surfaces of various heights and for permitting the abrading implement when operating on work having a shoulder to move down exactly to such shoulder without danger of breakage; and to provide such machine with its mechanism disposed to offer minimum obstruction to movement of the work on the supporting bed.

A specific embodiment of this invention is shown in the drawings in which:

Figure 1 is a side elevation of the machine partly in section with attachments for holding a file or a honing tool for which the operation requires reciprocating movement only.

Fig. 2 is a sectional detail taken on the line 2—2 of Fig. 1 showing how the file blade is backed up by an abutting element.

Fig. 3 is a detail viewed from the line 3—3 of Fig. 1 illustrating a form of crank arm adjustment for regulating the stroke of the reciprocating plunger.

Fig. 4 is a view corresponding to Fig. 1 showing alternative attachments that are especially designed for use with an abrading implement that has both rotary and reciprocatory movements, and also showing a modified form of the adjustable pitman crank whereby the stroke adjustment is effected from the outside by means of a stem extending longitudinally through the crank shaft.

Fig. 5 is a detail of the crank adjusting mechanism as viewed from line 5—5 of Fig. 1.

Fig. 6 is a fragmentary elevation of the stroke adjustment indicator.

In the drawings only those parts of the machine that are essential to an understanding of the present invention are illustrated.

The machine comprises a horizontal table or work support bed 1 mounted on trunnions 2 on the frame 3 in such manner that the table 1 can be tilted slightly and secured in its tilted position as by clamp screws, not shown, engaging the quadrant 4.

The frame 3 supports a housing 5 enclosing

pitman mechanism for reciprocating a plunger 6 which rides in bearings 7 and 8 so as to stand vertically and reciprocate longitudinally. The housing 5 is arranged to permit the pitman mechanism to run in oil. The plunger 6 has a shaft-like extension 9, extending upwardly through a central hole 10 in the bed 1. The part 9 of the plunger is channeled at 11 to receive splines 12 and 13 carried by spaced heads 14 and 15 of a yoke structure for mounting the abrading tools. The heads 14 and 15 are rigidly connected to each other by a rod 16 and set screws 17.

The lower head 15 is supported by an abutment in the form of a collar 18 fixed on the plunger portion 9.

The head 14 is formed on its front end for supporting a chuck 20 for holding a file 21 or other abrading implement of similar nature. The lower yoke 15 is provided with a forwardly facing chuck 22 for adjustably holding an abutment rod 23 which braces the file 21 against yielding laterally through pressure on the work. The rod 23 is adjusted by means of a set screw 24.

The yoke structure is normally held firmly pressed against the abutment collar 18 by means of a compression spring 25 and a nut 26 threaded on the upper end of plunger part 9. This spring is sufficiently stiff to overcome the frictional resistance of the file or other abrading element on the work but to yield in case of overtravel of plunger 9 in the event that the abrading element strikes a shoulder on the work, which in the drawings is represented as shouldered punch die 27 having a vertical surface 28 on which the file is positioned to operate and having a shoulder 29 which abruptly meets the surface 28.

An antifriction roller 30 engages rod 16 of the yoke structure and thus prevents the pressure of the work against the tool from causing the plunger rod 9 to yield laterally. The roller 30 is carried by an arm 31 mounted for vertical adjustment by means of a set screw 32 on a bracket 33 which in turn has a slotted base 34 and studs 35 for attachment to the bed 1 and adjustment toward and away from the plunger part 9. These adjustments permit the roller 30 to serve as a guide for the rod 16 in any position of adjustment to which the bed 1 may be tilted for operation of the abrading implement upon an inclined surface.

The pitman mechanism comprises a yoke 36 attached to the plunger 6 by a set screw 37 and having a slide bearing 38 that engages the crank pin 39 on the crank shaft 42, the crank arm being

preferably adjustable for regulating the vertical stroke of the plunger 9 and accordingly regulating the vertical stroke of the abrading implement.

In order to provide an adjustable crank arm, the crank pin 39 is eccentrically mounted on a flanged disc 40 which fits the circular periphery of a circular disc 41 eccentrically mounted on the crank shaft 42 which carries a drive pulley 43 belted to the source of power. In the form of crank eccentricity adjustment that is shown in Figure 1, the eccentricity of the crank is adjusted by means of a set screw 40.1 which engages a groove in the periphery of the eccentric 41 and is reached by a socket wrench through an aperture 40.2 in one side of the housing 5, and is adjusted by trial and observation until the reciprocatory movement of the plunger is of a desired amount.

In Fig. 4, alternative attachments for use with a rotating abrading implement are illustrated and also a modified form of crank arm adjustment mechanism for the pitman mechanism. In this form the crank arm is elbow-jointed and comprises a main arm 44 keyed to the crank shaft 45 and a swingable arm 46 pivoted eccentrically at 47 on the arm 44.

The swingable arm 46 is fast on a gear 48 which meshes with a pinion 49 fast on a stem 50 extending centrally through the crank shaft 45. The drive pulley 51 is keyed to the crank shaft 45 and in this case it may be a double pulley with one groove for the power belt 52 and a second groove for the tool-driving belt 53.

In Fig. 5 the arrow 45.1 indicates the normal rotation about the crank shaft 45 and stem 50 and the arrow 46.1 indicates the movement of the crank pin 55 as its eccentricity is adjusted.

A knob 54, keyed to the stem 50, serves to rotate the stem with respect to the crank shaft 45 for adjusting the eccentricity of the crank pin 55. A lock nut 56 clamps the knob 54 against a shoulder at the end of shaft 45 and thus locks the stem 50 in any position of adjustment with respect to the crank shaft 45 and at the same time locks the crank pin 55 at its adjusted eccentricity.

Stops shown in Figure 6 in the form of lugs 57 and 58, limit the rotation of the knob 54 with respect to the crank shaft 45 and restrain the movement so that the peripheral graduations on the knob 54 will correspond with the eccentricity of the crank pin 55.

In order to facilitate the assemblage and rearrangement of the mechanism above the work bed 1, the plunger stem is made in two parts, the part 6 which extends into the housing 5 and the part 9 which extends upwardly through the bed plate 1 and which terminates in a threaded stud 60 which screws into a socket in the upper end of the part 6 and terminates at a shoulder 61. This shoulder assures that the parts splined on the upper part 9 will face the front 62 of the bed 1. For convenience in connecting these parts one or both of the parts 9 and 6 may be shaped as at 63 to receive a wrench.

Referring again to Fig. 4, the change to a rotary abrading implement, as for example, a grinding wheel 64, involves the use of a spindle 65 and chuck 66 in place of the chuck 20 of Fig. 1. In order to provide a bearing for the spindle 65, the upper head 14 is equipped with a bushing 67 and the spindle is confined in said bushing by means of set collars 68 and 69 and a pulley 70.

A second bearing member 71 for the spindle 65 has a radially extending shank 72 which replaces the abutment rod 23 in the lower head 15 of the yoke structure. The bracket 33 is replaced by a bracket 73 on which is shiftably mounted a pair of guide pulleys 74 for the belt 53.

In the form shown, the pulleys 74 are carried by a swingable arm 75 which is normally urged by a compression spring 76 to take up slack in the belt 53. The spring 76 may be mounted on a guide arm 77 pivoted on the bracket and extending through an aperture in the arm 75.

The operation of the device shown is as follows:

The operator stands in front of the bed plate and places the work in position to cooperate with the abrading tool and after making the proper adjustment of the machine for the particular surface he is working on, he pushes the work toward the abrading implement and guides the work so that the abrading implement will perform the proper finishing operation according to the operator's judgment.

In preparing for a filing operation, the stroke of the pitman mechanism is first adjusted to a throw that is somewhat less than the height of the surface 28 of the part of the work that is being operated upon. Then the pitman mechanism is moved by turning the pulley 43 until the plunger 6 is at the lower limit of its stroke and the cross-head structure is adjusted on the plunger part 9 by means of the collar 48 so that the file 21, or hone as the case may be, will rest upon the shoulder 29 of the work, if there be such a shoulder.

If the surface 28 is inclined slightly from the vertical, the bed 1 will be tilted to bring the surface 28 into vertical position when the work 27 rests on the bed and the guide roller 30 will be adjusted by shifting the bracket 33 and adjusting the arm 31 vertically so that the roller 33 will guide the stem 16 and will be clear of the heads 14 and 15 throughout the stroke of the pitman mechanism.

After these adjustments are made, the compression spring 25 is adjusted by means of the knurled collar 26 until it exerts pressure enough to overcome any resistance that is likely to be applied by the abrading action of the file but allowing opportunity for the yoke system to yield in the event that the file should strike the surface 28 before the pitman mechanism has reached the lower limit of its stroke. It is to be noted that the lower end of the file is braced laterally by the abutment rod 23 so that there can be no yielding of the file under pressure against the work, and that the yoke structure is backed up by the guide roller 30 so that there can be no similar yielding of the stem part 9. This insures that the movement of the file will always be exactly in vertical lines.

In operating with a rotary abrading implement 64, the parts function in the same way as they do in the filing operation except that the abrading implement rotates as it reciprocates vertically.

Although but one specific embodiment of this invention is shown in the accompanying drawings with modified attachments for providing for rotation of the abrading implement during its reciprocatory movement, it will be understood that numerous details of the construction shown may be altered or omitted without departing from the spirit of the invention as defined by the following claims.

I claim:

1. A machine of the class described comprising a work supporting bed, a longitudinally reciprocatable vertical plunger, a yoke slidably mounted on said plunger above said bed, a shoulder on said plunger carrying said yoke, an abrading implement carried by said yoke at one side of said plunger, and a spring stop normally urging said yoke against said shoulder.

2. A machine of the class described comprising a work supporting bed, a longitudinally reciprocatable vertical plunger, a yoke slidably mounted on said plunger above said bed, a shoulder on said plunger carrying said yoke, an abrading implement carried by said yoke, a spring stop normally urging said yoke against said shoulder, and local guide means on said bed opposed to said abrading implement to support said plunger against lateral yielding through pressure against said abrading implement.

3. A machine of the class described, comprising a work supporting bed, a longitudinally reciprocatable vertical plunger, a yoke structure having a pair of heads splined on said plunger, a supporting shoulder on said plunger for said yoke structure, a spring stop on said plunger normally urging said yoke structure against said shoulder, the upper said head having means for holding a vertically depending abrading implement and the lower said head having abutment means for resisting lateral yielding of said abrading implement toward said plunger.

4. A machine of the class described, comprising a work supporting bed, a longitudinally reciprocatable vertical plunger, a yoke structure having a pair of heads splined on said plunger, a supporting shoulder on said plunger for said yoke structure, a spring stop on said plunger normally urging said yoke structure against said shoulder, the upper said head having means for holding a vertically depending abrading implement, the lower said head having abutment means for resisting lateral yielding of said abrading implement toward said plunger, means adjustably connecting said heads together, and guide means on said bed coacting with said head connecting means to support said plunger against lateral yielding through pressure on said abrading implement.

5. A machine of the class described, comprising a work supporting bed, a longitudinally reciprocatable vertical plunger, a yoke structure having a pair of vertically spaced heads splined on said plunger, a supporting shoulder on said plunger for said yoke structure, a spring stop on said plunger normally urging said yoke structure against said shoulder, a rotary vertical spindle,

bearings on said heads for said spindle, and adjustable guide means on said bed for preventing lateral yielding of said spindle.

6. A machine of the class described comprising a work supporting bed, a longitudinally reciprocatable vertical plunger, a yoke slidably mounted on said plunger above said bed, a shoulder on said plunger carrying said yoke, an abrading implement carried by said yoke, a spring stop normally urging said yoke against said shoulder, and local guide means on said bed opposed to said abrading implement to support said plunger against lateral yielding through pressure against said shoulder, said bed being tiltable relative to the axis of said plunger, and said guide means being adjustable to conform to the changes in angular disposition of said bed.

7. A machine of the class described, comprising a work supporting bed, a longitudinally reciprocatable vertical plunger, a yoke structure having a pair of vertically spaced heads splined on said plunger, a supporting shoulder on said plunger for said yoke structure, a spring stop on said plunger normally urging said yoke structure against said shoulder, a rotary vertical spindle, bearings on said heads for said spindle, a pulley on said spindle, a drive belt for said pulley, guide means comprising a bracket secured to said bed and shiftably toward and away from said plunger, and a roller overhanging said bed, being adjustable vertically on said bracket and coacting with said yoke structure to resist lateral yielding of said spindle.

8. A machine of the class described, comprising a work supporting bed, a longitudinally reciprocatable vertical plunger, a yoke structure having a pair of vertically spaced heads splined on said plunger, a supporting shoulder on said plunger for said yoke structure, a spring stop on said plunger normally urging said yoke structure against said shoulder, a rotary vertical spindle, bearings on said heads for said spindle, a pulley on said spindle, a drive belt for said pulley, guide means comprising a bracket secured to said bed and shiftably toward and away from said plunger, and a roller overhanging said bed, being adjustable vertically on said bracket and coacting with said yoke structure to resist lateral yielding of said spindle, guide pulleys shiftably mounted on said bracket, and a spring normally urging said guide pulleys into position to take up slack in said drive belt due to reciprocation of said yoke and to adjustment of 55 said bracket on said bed.

LEOPOLD F. GLAUDE.
